UNITED STATES PATENT OFFICE

HOWARD S. GERKEN, OF BUFFALO, NEW YORK, ASSIGNOR, BY DIRECT AND MESNE ASSIGNMENTS, TO GRAVEL PRODUCTS CORPORATION, OF BUFFALO, NEW YORK, A CORPORATION OF NEW YORK

APPARATUS FOR WASHING, SEPARATING, AND GRADING MATERIALS

Application filed February 27, 1926. Serial No. 91,207.

This invention relates to improvements in apparatus for washing and separating or grading materials, as for instance, sand and gravel from waterways.

5 One object of the invention is to provide a practical and efficient apparatus for the purpose stated adapted to thoroughly and expeditiously wash, separate and grade sand and gravel or the like at the source of supply and 10 deliver the separated materials to suitable receptacles in a clean condition substantially free from excess water.

Other objects of the invention are to provide an apparatus of this sort adapted to first 15 separate the undesirable material from that to be retained and then treat the latter to separate the coarser material from the fine material and pass the fine material to means for adding a relatively large volume of water 20 thereto at considerable velocity, so as to agitate the fine material and wash and carry away the dirt and undesirable foreign matter; also to provide means for this purpose in the form of settling boxes or receptacles 25 for the reception of the washed fine material, and also to provide automatic means for intermittently dumping this washed material without discharging any substantial quantity of the washing water therewith from the 30 settling boxes; and also to provide an apparatus of this sort having an upper trough for effecting the primary washing of the material and separating therefrom the coarse refuse, a lower trough for receiving a portion of the 35 desired material, means between said upper and lower troughs for separating a part of the desired material and discharging the same from the apparatus, and means for receiving the remaining desired material and 40 delivering it to said lower trough; also to provide the troughs with separate, spaced, separating and washing units which are constructed and adapted to be interchangeably mounted on said troughs so that these units 45 can be changed from one position to another on either trough in accordance with the kind or condition of the material to be washed, separated and graded.

Further objects are to construct a washing, 50 separating and grading apparatus particu-

larly adapted to be used on a boat or scow, so that it can be positioned lengthwise of the boat over the hold or hatches, whereby the washed, separated material can be discharged from the apparatus into separate compartments in the hold, or delivered to one or another part of the hold as may be desired to segregate the different grades of material or evenly load the boat; and to construct the supporting means so that said means and the apparatus can be moved bodily to a lateral position on the boat to permit unobstructed access to the hold of the boat through the hatches; and also to construct said supporting means for said apparatus, so that the same 55 may be collapsed or lowered to permit the passage of an unloading or other apparatus on the boat over said washing, separating and grading apparatus, and to form a compact unit having its center of gravity disposed 60 close to the deck to avoid swaying or dislocation of the apparatus in rough weather.

Other objects are to improve and simplify apparatus of the sort described in the other respects hereinafter specified and claimed. 65

In the drawings:-

Fig. 1 is a side elevation of a material washing, separating and grading apparatus embodying the invention arranged lengthwise over the hatches of a boat, a portion of 80 which is shown in section.

Fig. 2 is a similar view thereof in its collapsed or inoperative position at one side of the boat.

Fig. 3 is a fragmentary plan view of the 85 boat with the apparatus in operative position above the holds or hatches of the boat.

Fig. 4 is a transverse section of the upper 90 portion of the boat showing the apparatus in operative position amidship in full lines, and in its collapsed, inoperative position at one side of the boat in broken lines.

Fig. 5 is an end elevation, on an enlarged 95 scale, of the material receiving end of the apparatus.

Fig. 6 is a transverse, vertical section of the apparatus, on line 6—6, Fig. 7.

Fig. 6^a is a detail transverse section, on an 100 enlarged scale, of the means for adjustably

supporting the lateral separating screens of the apparatus.

Fig. 7 is a fragmentary, longitudinal, vertical section thereof, on line 7—7, Fig. 3, on 5 an enlarged scale.

Fig. 8 is a sectional plan view of one of the primary separating units of the apparatus on line 8—8, Fig. 9.

Fig. 9 is a transverse section thereof on line 10 9—9, Fig. 8.

Fig. 10 is a sectional plan view showing one of the washing and settling boxes or units of the apparatus on line 10—10, Fig. 11.

Fig. 11 is a transverse section thereof on 15 line 11—11, Fig. 10.

Fig. 12 is a plan view of a baffle plate used in the primary separating units.

Fig. 13 is a longitudinal, vertical section, on an enlarged scale, of one of the primary 20 separating units, on line 13—13, Fig. 8.

Fig. 14 is a plan view of one of the intermediate separating and grading screens or units of the apparatus, on line 14—14, Fig. 6, on an enlarged scale.

Fig. 15 is a fragmentary, sectional plan view thereof on line 15—15, Fig. 6.

Fig. 16 is a fragmentary, transverse, vertical section thereof, on line 16—16, Fig. 14, showing the same detached from the apparatus.

Fig. 17 is a longitudinal section thereof, on line 17—17, Fig. 18.

Fig. 18 is a fragmentary, transverse section thereof, on an enlarged scale, on line 35 18—18, Fig. 14.

The material washing, separating and grading apparatus embodying the invention is preferably installed on a boat or scow and comprises, generally, a pump 10 arranged on 40 the boat A, and adapted to suck sand, gravel and water from the bed of a river or other body of water, through any usual nozzle and hose 12 and deliver these materials through a standpipe or passage 13 to the upper end 45 of an inclined chute or flume 14. This flume extends lengthwise of the boat over the hatchways B of the hold C which preferably is divided into compartments for receiving the separated and graded materials. The chute 50 14 is rigidly mounted on a series of transverse, vertical and movable supports or frames 11, 11^a and 11^b which will be described later.

Coarse separating or screening units 15 are arranged in spaced relation along the bottom 55 of the chute 14 through which screens pass all of the gravel and sand which are to be retained, together with a part of the water, while the rocks and other undesirable, coarse refuse material pass over the screens with a portion 60 of the water and are discharged from the lower end of the chute into a hopper or box 16 and thence to a passage or pipe 17 through which it is conducted overboard.

Arranged lengthwise beneath the chute 14 65 and also rigidly supported on the frame 11,

11^a and 11^b is a trough 20, preferably of substantially the same size as the chute 14, and 70 21 represents inclined screens or separating units which may be arranged in pairs, with each pair of screens extending laterally and downwardly in opposite directions from the chute 14 immediately below one of the screening units 15. These lateral screens 21 are adapted to receive material and water from said screens 15 and permit the gravel or coarse 75 portions of the material to tail off over their lower ends and fall into the desired compartments in the hold C, while the water and sand or other fine material passing through these screens may be received upon inwardly inclined and transversely arranged trays or 80 plates 23 which direct the sand and water into the lower trough 20. The trough 20 is provided with spaced washing and settling boxes or units 24 depending from the bottom of the trough and into which the sand collects and is washed and from which it is intermittently discharged into receiving compartments in the hold, as will be explained later.

The upper screening units 15 can be of any suitable construction adapted for the purpose, those shown comprising grates or screens 15^a formed of bars 25 extending lengthwise of the chute 14 and spaced apart according to the size of material to be accepted, and rigidly connected by end cross bars 26. Each screen 15^a, see Figs. 8, 9 and 13, is removably supported in a rectangular frame 27 having opposite end bars 28 and side bars 29. The side bars 29 are detachably secured to the undersides of the channels or members 30 forming the side walls of the chute 14, as by bolts or fastening devices 31. The ends of screen bars 25 are preferably seated or positioned in slots 32 formed by cutting away portions of the end bars 28, see Figs. 8 and 13, so as to provide portions which overhang said ends and prevent the accidental detachment of the screens.

The discharge of the material through the screen 15^a is preferably controlled by a pair of slide valves or gates 34 of suitable construction movable laterally in guides on bottom flanges 35 at the opposite ends of the frame 27, Figs. 9 and 13, so that by appropriate adjustment of these gates, the material can be discharged uniformly amidships, or towards one or another part of the hold to evenly load the boat, or by closing the valves in some of the units 15, the material will pass over these units and discharge into 110 other compartments. These gates are particularly useful when the lateral screens 21 are employed, as will be explained.

Due to the relatively high velocity of the water and material passing along the chute 125 14 over the screen units 15 constructed as thus far described, the material and water directed through said screens has a tendency to discharge obliquely forward and downward, and to spread laterally. It is desirable, however,

in the present separating apparatus, to be able to restrict the spread of the material so that it will not fall beyond the sides of the lower trough 20 and also to discharge the material downwardly substantially at right angles to the bottom of the chute 14.

Means are therefore provided for this purpose, the means shown comprising baffle plates 37, one of which is employed in each screening unit 15, and consists of a flat plate of substantially the size of the opening in the frame 27, adapted to be removably and loosely supported between the screen 15 and the gates 34 in such manner as not to interfere with the operation of said gates. Each baffle plate has a central aperture 38, the area of which is substantially less than the screen opening, whereby ledges or baffles 39 are provided at all four sides of the screen upon which some of the material and water impinges and which, in flowing inwardly over the ledges 39 toward the aperture 38, causes a counter current which intercepts and mixes with the material going directly through the aperture and turns it from its oblique and laterally spreading course and reduces its velocity, so that all of the material and water passing through each unit falls substantially straight down into the trough 20. This feature is particularly adapted for use when the lateral screens 21 and inclined plates 23 are omitted, and material is discharged directly to the washing and settling units 24.

Each of the lateral separating screens 21 includes a removable grate or screen formed of spaced rods 40 which extend laterally relatively to the chute 14 and are rigidly connected together by cross bars 41.

Each screen, see Figs. 14 to 18, is removably supported in a rectangular frame 42 in any suitable manner, as by engaging the ends of the rods 40 in notches or seats 43 in an end bar 44 of the frame, and the ends of the cross bars 41 in notches in the upper edges of the frame side bars 45, and securing the screen in this position by hook bolts 46 secured to said side bars 45 and engaging over the adjacent screen rods 40. The screen frames 42 are pivotally connected to each other and supported at their upper or inner ends by means of a hinge rod 48, arranged lengthwise substantially centrally beneath the chute 14 and bearing in depending, transverse plates 49, which are preferably bolted or otherwise detachably connected to the transverse frame bars 27 of the units 15, see Fig. 13.

As shown clearly in Figs. 6 and 18, the top surfaces of the screens 21 lie substantially flush with the upper edges of the lower end bars 44 of the frames 42, and the screen rods 40 are so spaced that, as the mixed material and water is discharged from the screening units 15 it flows downwardly on the screen 21, and the sand and water will pass between the rods 40 and fall upon the

inclined plates 23, while the gravel will travel down the screen 21 and tail off over the lower ends thereof and fall through the open hatches into the hold of the boat.

The upper or outer ends of the inclined trays or plates 23 are disposed beneath and adjacent the end bars 44 of the screens 21, while their inner ends rest on the top edges of the side walls 52 of the trough 20. In order to direct and confine all sand and water to said plates and prevent spilling thereof over the outer ends and the side edges of the plates, the latter are provided with upstanding side flanges 53, and a curved deflector 54 secured to the adjacent end bar 44 and having a notched upper edge extending upwardly between the screen bars 40, is adapted to intercept sand and water reaching the end of the screen and deflect it in the opposite direction downwardly along the plate 23.

Means are provided for permitting the inclined screens 21 to be adjusted to different inclinations, so as to retard or accelerate the velocity of the material passing over the screens and thus further control the separation of the material. That is, if the velocity is retarded, relatively more of the material will pass through the screens, while if the velocity is increased, less material will pass through. Thus, by adjusting the screens in accordance with the proportions of the mixture, the correct or desired separation can be accurately maintained.

For this purpose, each screen 21, in addition to being pivoted to the hinge rod 48, is also pivotally attached at its outer end to its companion plate 23, as by a pivot rod 56 passing through the ends of the side bars 45 of the screen and through lugs 57 at the outer corners of the plate 23, see Figs. 15 and 18. For holding the screens in their adjusted positions, each plate is preferably provided adjacent its lower end with a depending bar 58 having spaced notches 59 any one of which is engageable over a fixed upstanding projection 60 on the adjacent wall of the trough 20, see Figs. 6 and 61. Any other suitable means for adjustably holding the screens 21 and plates 23 may be used. Guard plates 61, see Fig. 18, are preferably secured to the side bars 45 adjacent the outer ends of the screens 21 to prevent the material from passing laterally off the plate 23 as it strikes the deflector 54.

The washing and settling boxes 24 for the sand or fine material will now be described. Each box, see Figs. 6, 7 and 11, comprises a hopper 62, open at top and bottom and having a sloping rear wall 63, an upright front wall 64, and side walls 65 which are preferably inclined inwardly towards the bottom as shown. The hopper has side and end flanges 66, 67 respectively at its top by which it is secured to the bottom of the trough 20 beneath a discharge opening 68 in the trough 130.

20 as by bolts 69. If desired, the opening 68 may be provided with a screen or grate 70.

5 Discharge of the material from the settling boxes is controlled by valves at the bottoms of the boxes. Each valve preferably consists of a pan or shallow receptacle 72 extending across the lower open end 71 of the hopper and secured to the lower ends of upright straps 73. The valve is adapted to have a 10 limited movement downwardly away from the open end 71 of the hopper, as by connecting the upper ends of the straps 73 to the ends of a pair of levers 75, see Figs. 11 and 15, which are secured to a rock shaft 76 on 15 the top of the trough 20 and to which is secured an arm provided with an adjustable counterweight 77. This weight normally holds the valve in a substantially closed position with material therein surrounding the 20 open end 71 of the hopper, and the valve being adapted to open in a manner to be explained later.

An important feature of the construction described is that the upper screening units 15, 25 lateral inclined screens 21 and associated inclined plates 23, and the washing and settling boxes 24 are all constructed so as to be interchangeably attached to the chute 14 or trough 20 so that any of these units can be 30 positioned either on said chute or on said trough as desired, depending on the character of the material to be separated. For this purpose the spaces in the bottoms of said chute and trough, between the different units 35 mounted thereon, are closed by removable bottom plates or members 79, the length of which is substantially the same as the length of the supporting frames 27 for the units 15 or the frames 64 of the settling box units 24. 40 The holes in the chute 15 and trough 20 for the securing bolts for said units and for the bottom plates 79 in the chute 14 and trough 20 are all on like centers, and the various units and plates can therefore be shifted and secured in different relative positions as desired.

In the use of the washing, separating and grading apparatus, as thus far described, and assuming that material comprising sand, 50 gravel and water is to be treated, the mixture from the nozzle 12 is delivered under pressure by the pump 10 to the upper end of the chute 14, while water alone and under pressure is preferably discharged into the trough 20, through a pipe 13^a from another pump 10^a, Fig. 3.

In the particular arrangement shown in 60 Figs. 1 and 3, there are no lateral screens associated with the screening units 15 at the left or upper end of the chute 14, and the sliding gates 34 for these units will, therefore, be closed to allow all of the material to pass over these units to the units at the lower or right 65 hand end of the chute 14 and the settling

boxes beneath the closed units 15 will be inactive.

The material is thoroughly agitated in its 70 passage down the chute 14, and the gravel which is small enough will pass with the sand and some of the water through the screening units 15, while the large stones and débris will be carried with the bulk of the water over these units and be directed overboard through the box 16 and passage 17. The 75 gravel, sand and water accepted by the screening units 15 will be discharged upon the lateral separating screens 21, the gravel traveling over the top surfaces thereof and tailing off over their lower ends, while the sand and the water will pass through these screens and be directed by the inclined plates 23 into the trough 20, and the sand will then gravitate 80 over the inclined walls 63 of the washing and settling boxes 24 and upon the valves or pans 85 72.

In apparatus heretofore used, the sand and water were discharged directly into the hold or compartments of the boat, the water being gradually displaced by sand settling in 90 the hold until the water finally overflowed the hatch coamings and thence went overboard. This method, however, permitted mud and other sediment to remain with the sand and prevented the sand from being 95 retained in a clean condition.

The provision of the washing and settling boxes of the present invention, however, enables the sand to be thoroughly washed and the mud and sediment removed before it is 100 discharged from the trough 20, and also permits the sand to be delivered to the hold with a minimum of water. This is accomplished as follows.

As the sand and more or less muddy water 105 is deposited in the trough 20 from the plates 23, it is met by the current of water discharged from the pipe 13^a which, flowing into the boxes causes a thorough agitation of the material, and the sand gradually settles upon the valves 72, while the mud is held in suspension and is carried away down the trough with the water. The valves 72 are so counterbalanced by the weights 74 that the receptacles 72 and also a considerable portion of the hoppers are filled with sand before the weight of sand and water is sufficient to overcome the counterweights and permit the valves to descend. As the valves descend, some of the sand spills out over the edges of the valves, 110 and owing to the consequent reduction in the weight of sand in the boxes, the counterweights will return the valves to substantially closed position, as in Fig. 11, before all of the sand has been dumped. Therefore, there is 115 always a layer of sand in the valve or receptacle 72 sufficient to seal the lower end of the settling box hopper and prevent the water above the sand from flowing out of the bottom of the box and into the hold with the sand. 120 125 130

The action of the valves is entirely automatic, and they need no attention other than to adjust the weights in accordance with the work in hand. For example, if sand only is to be separated from coarse material and washed, 5 the units 15 and settling boxes 24 would be arranged as shown at the left hand side of Figs. 1 and 3, so that the sand would pass directly through the screens 15^a into the settling boxes. For this work, the baffle plates 10 37 are particularly advantageous for preventing the spilling of the material. The sand upon reaching the trough 24, would be subjected to the washing action of the stream of water therein, and be thoroughly cleaned 15 before being discharged into the hold.

The various units of the apparatus can be arranged in still other ways for particular purposes, and the lateral screens 21, by reason 20 of the detachable, transverse supporting plates 49, are readily removable so as to be positioned on any of the units 15.

The transverse supporting frames 11, 11^a and 11^b before mentioned, are preferably of 25 A shape as shown, each having upright spaced legs 80 connected by upper and intermediate horizontal cross members 81, 82, upon which the chute 14 and trough 20 respectively are disposed at successively lower elevations to 30 provide the required inclination for said chute and trough.

It is desirable that the washing, grading and separating apparatus be capable of transverse movement relatively to the length of the 35 boat in order that it may be positioned over different portions of the hatchways as necessary. Also, when desired, the apparatus should be movable to a position over the deck at one side of said hatches, so as to leave the 40 hatches entirely unobstructed to permit the use of unloading apparatus for removing the cargo.

For this purpose, the lower ends of the frame legs 80 are connected to trucks or supports 83 having wheels or rollers 84 adapted 45 to travel on guide tracks or rails 85 mounted on the transverse hatch coamings or other parts of the boat. Removable extension rails or tracks 86, Figs. 3 and 4, are arranged 50 transversely of the deck at one side of the boat, and are disposed in line with the track rails 85, whereby the entire apparatus can be moved laterally by first disconnecting the pipes or passages 13, 13^a, and the connections 55 for the discharge passage 17.

Preferably the legs 80 of one or more of the supporting frames are of knockdown construction, as by forming each leg of two parts connected by a detachable gusset or 60 plate 88, see Fig. 5, so that, by disconnecting the gussets and the lower portions of the legs, as shown in dotted lines in said figure, the chute 14 and trough 20 with their attached separating units, may be lowered substantially to the horizontal position shown

in Fig. 2, and in dotted lines at the right of Fig. 4. By this arrangement, the apparatus can be reduced in height when not in use, and when positioned at the side of the boat, unloading apparatus indicated by dotted lines in Fig. 4, can be moved along the boat over the washing, grading and separating apparatus. Also the apparatus, thus collapsed, lies close to the deck, where it can be securely lashed in place to prevent swaying 75 or dislocation thereof during rough weather.

It will also be noted by reference to Fig. 4, that the washing, separating and grading apparatus is of relatively narrow dimensions laterally, and is of such compact form that 80 unloading or other apparatus can pass freely over the same while in its amidships position without collapsing or otherwise disturbing the washing, separating and grading apparatus.

I claim as my invention:—

1. In an apparatus of the character described, the combination of a substantially unobstructed inclined chute into which the material is introduced, a screen in the bottom thereof through which material passes, a substantially unobstructed trough disposed below said chute and inclined in substantially the same direction, a material washing and settling unit in the bottom of said trough into which material is delivered from said screen, means for introducing a stream of water into said unit to wash the material and remove refuse therefrom, and means for automatically and intermittently discharging 95 washed material from said settling unit.

2. In an apparatus of the character described, the combination of an inclined chute into the upper portion of which solid material to be separated and water are delivered 105 and along which they are adapted to flow at a relatively high velocity, a series of screens in the bottom thereof over which the material passes in succession and through each of which some of the water and a portion of the material of all grades to be retained may pass and over which the refuse material is moved down the chute by the water, an inclined secondary screen arranged to receive the material passing through each of said first screens and through which water and fine material pass to separate the coarse material from the fine material, a trough arranged beneath and inclined in substantially the same direction as said chute 110 to receive the material passing through each of said first screens and through which water and fine material pass to separate the coarse material from the fine material, a trough arranged beneath and inclined in substantially the same direction as said chute to receive said fine material passing through said inclined secondary screen, and a washing and settling unit associated with said trough into which the fine material and water are directed, and from which the refuse is 120 washed out and carried therefrom down the trough while the washed material is permitted to settle in said unit.

3. In an apparatus of the character described, the combination of a substantially 125

unobstructed inclined chute into the upper portion of which solid material to be separated and water are delivered and along which they are adapted to flow at a relatively 5 high velocity, a succession of screens in the bottom thereof through which the material to be retained passes and over which the refuse material is moved down the chute by the water, a lateral inclined screen arranged to 10 receive the material passing through each of said first screens and through which water and fine material pass to separate the coarse material from the fine material, an inclined member upon which the fine material and 15 water fall, a trough into which said inclined member delivers said fine material and water, a washing and settling unit associated with said trough into which said fine material and water are directed and from which the 20 refuse is washed out and carried away therefrom by the water while the washed material is permitted to settle in said unit.

4. In an apparatus of the character described, the combination of an inclined chute 25 into which solid material and water are introduced, a succession of spaced screens in the bottom of said chute through which the material to be retained and a portion of the water pass while the refuse material is moved over 30 said screens by the water, an inclined screen arranged to receive the material passing through each of said first screens and which is constructed to separate the coarse material from the fine material and water, a trough 35 into which said fine material and water passing through said inclined screens are delivered, a washing and settling unit associated with said trough into which the fine material and water are directed, means for delivering 40 an additional volume of water to said trough for agitating and washing the material in said unit and removing the refuse therefrom while said washed material is permitted to settle in said unit.

45 5. In an apparatus of the character described, the combination of an inclined chute into which solid material and water are introduced and along which they are caused to flow at a relatively high velocity, a screen in 50 the bottom thereof through which the material to be retained and some of the water pass and over which the refuse material is moved along down the chute by a relatively large portion of the water, an inclined screen which 55 is arranged to receive said material and water from said first screen, and is constructed so that the coarse material passes over the same and is discharged from the end thereof by the velocity of the material, while the fine 60 material and water pass through said screen, an inclined member upon which the fine material falls, a trough extending lengthwise beneath said chute and inclined in substantially the same direction and into which said inclined member directs said fine material, and a 65

washing and settling unit associated with said trough into which said fine material is washed and the refuse removed therefrom while the washed material is permitted to settle in said unit.

6. In an apparatus of the character described, the combination of an inclined chute 70 into which solid material and water are introduced, a screen in the bottom thereof through which the material to be retained passes, an inclined screen arranged to receive the material and water passing through said first screen under momentum and which is constructed to separate the coarse material from the fine material, a second chute extending 75 lengthwise below said first chute and inclined in substantially the same direction, an inclined member adapted to receive fine material and water passing through said inclined screen and direct them into said second chute, 80 a pivotal support for said inclined screen, a pivotal connection between said inclined screen and said inclined member, and means adapting adjustment of said parts about said pivots to vary the inclination of said inclined 85 screen to change the velocity of the material passing thereover and thereby control the separation of said material.

7. In an apparatus of the character described, the combination of an inclined chute 90 having a screened opening in the bottom thereof over which the material is passed in a current of water at a relatively high velocity and which is constructed to permit the desired material to pass therethrough with water, and a flat baffle plate which is arranged beneath substantially parallel with and close to said screen and has an extended aperture therein of substantially less area than said opening so as to provide ledges extending 95 into said opening adapted to intercept a portion of the material and water passing through said opening for directing the material and water substantially perpendicularly 100 downward from said opening in said chute and minimize lateral spreading of said material and water.

8. In an apparatus of the character described, the combination of an inclined chute 110 to the upper part of which the water and solid material are delivered and along which they flow at a relatively high velocity, a plurality of separating screens in the bottom of the chute over which the refuse material is moved in succession by the water and through which the material to be retained passes, an inclined trough disposed below said chute, a plurality of inclined separating screens extending laterally from beneath said chute and each arranged to receive the material passing through one of the first screens, means for conducting material passing through said lateral screens to said trough, and a plurality of washing and settling units in the bottom of 115 said trough, said first mentioned screens and 120

125

130

said washing and settling units being removably mounted and adapted to be interchanged one with the other on said chute and trough, and said lateral screens being detachably and 5 interchangeably mounted.

9. In an apparatus of the character described, the combination of a substantially unobstructed inclined chute throughout the length of which water and solid material are 10 adapted to flow at a relatively high velocity, a plurality of spaced apart separating screens in the bottom thereof, an inclined trough disposed below said chute, inclined separating screens mounted on and extending laterally 15 from the under side of said chute, means connected to said lateral screens for conducting material from said lateral screens to said trough, and a plurality of washing and settling units in the bottom of said trough, said 20 first mentioned screens and said washing and settling units being removably mounted and adapted to be interchanged one with the other on said chute and trough, and said lateral screens being detachably and interchangeably mounted on said other screens. 25

10. In an apparatus of the character described, the combination of an inclined chute, a plurality of separating screens in the bottom thereof, an inclined trough disposed below said chute, a plurality of washing and separating units in the bottom of said trough, and a plurality of imperforate bottom plates detachably secured in said chute and trough to alternate with and separate said screens 35 and said washing and separating units, said plates, said screens and units being of substantially the same length and constructed and adapted to be interchanged one with another on said chute and said trough.

40 11. In an apparatus of the character described, the combination of a pair of troughs arranged one below the other and each having separating instrumentalities mounted thereon, and a plurality of spaced, transverse 45 supporting members on which said troughs are secured so as to incline lengthwise, a supporting member to which the lower ends of both troughs are secured, and other supporting members arranged in spaced relation to said first support and to which said troughs are also secured, said other supporting members being collapsible so as to permit said troughs to be lowered while being supported at said lower end on said end support to a 50 substantially horizontal position at the elevation of their lower ends.

12. In an apparatus of the character described, the combination of a pair of troughs arranged one below the other and each having 55 separating instrumentalities mounted thereon, and a plurality of spaced, transverse supporting members on which said troughs are secured so as to incline lengthwise, a supporting member to which the lower ends of both troughs are secured, other supporting mem-

bers arranged in spaced relation to said first support and to which said troughs are also secured, said other supporting members being collapsible so as to permit said troughs to be lowered while being supported at said lower end on said end support to a substantially horizontal position at the elevation of their lower ends, and transverse roller trucks for said supports adapted to permit said apparatus to be moved transversely in either the 70 raised or lowered position of said troughs. 75

13. In an apparatus of the character described, the combination with a boat, of a pair of troughs arranged one below the other and adapted to extend lengthwise over the 80 hatches of the boat, separating instrumentalities on said troughs adapted to wash, separate and grade material and discharge the same through said hatches, spaced supporting members which extend transversely of said troughs and to which said troughs are secured so as to incline lengthwise, and transverse roller trucks for said supports whereby said apparatus can be moved laterally to a position on the boat at one side of said hatches 85 to leave the hatches unobstructed.

14. In an apparatus of the character described, the combination with a boat, of a pair of troughs arranged one below the other and adapted to extend lengthwise over the hatches 90 of the boat, separating instrumentalities on said troughs adapted to wash, separate and grade material and discharge the same through said hatches, spaced supporting members which extend transversely of said troughs and to which said troughs are secured so as to incline lengthwise, one or more of said supporting members being collapsible to permit said troughs to be lowered to a substantially horizontal position without disconnecting said troughs or said separating instrumentalities, and transverse roller trucks for said supporting members adapted to permit said apparatus to be moved laterally in either the raised or lowered position of said 100 troughs to a position at one side of said hatches to leave said hatches unobstructed. 105

15. The combination with a boat, of apparatus arranged over the hold thereof and comprising an inclined chute extending lengthwise of the boat, means for introducing solid material and water into the upper portion of said chute, screens in the bottom thereof at different points along the chute through which screens material to be retained passes and over which refuse material and a portion of the water pass down the chute, an inclined secondary screen arranged to receive the material from each of said first screens and through which the fine material passes to separate it from the coarse material which discharges over the screen into the boat, a trough extending lengthwise of the boat below said chute and into which said fine material and water passing through said in- 115 120 125 130

clined screens are received, and washing and settling units along the bottom of said trough into which the fine material and water are directed and from which the refuse is washed out and carried away therefrom along said trough while the washed material is permitted to settle in said units, said unit being adapted to discharge said washed material into said hold.

10 16. In an apparatus of the character described, the combination of a substantially unobstructed inclined chute, means for delivering water and solid material to the upper portion of the chute and causing them to flow down the chute at a relatively high velocity, a succession of primary screens along the bottom of the chute and over which the material passes in succession and through which some of the water and material pass 15 while the refuse material is moved along down the chute over said screens by the water, secondary screening means arranged to separately receive the water and material passing through each of the primary screens and deliver the coarse material tailing off of the secondary screening means to a desired point, means arranged to receive the water and finer material passing through said secondary screening means and direct the same to a different point, and means for selectively regulating as desired the quantity of material 20 passing through the different primary screens.

17. In an apparatus of the character described, the combination of a substantially unobstructed inclined chute, means for delivering water and solid material to the upper portion of the chute and causing them to flow down the chute at a relatively high velocity, 25 a succession of screens along the bottom of the chute over which the material passes in succession and through which some of the water and material pass while the refuse material is moved along down the chute over said screens by the water, an inclined second chute arranged lengthwise below said first chute, secondary screening means arranged to separately receive the water and material passing through each of said chute screens 30 and direct the coarse material tailing off of the secondary screening means away from said second chute, the water and finer material passing through said secondary screening means being received and conducted by said second chute away from the tailings from 35 said secondary screening means, and controlling means for selectively regulating the quantity of material passing through the different chute screens as desired.

60 18. In an apparatus of the character described, the combination of a substantially unobstructed inclined chute, means for delivering water and solid material to the upper portion of the chute and causing them to flow 65 down the chute at a relatively high velocity,

a succession of primary coarse screens along the bottom of the chute and over which the material passes in succession and through each of which some of the water and a portion of the material of all grades to be retained 70 may pass while the refuse material is moved along down the chute over said screens by the water, an inclined second chute arranged lengthwise below and substantially parallel to said first chute, and a plurality of secondary 75 finer screens each arranged to receive the water and solid material passing through one of the primary screens and deliver the coarse material tailing off of the secondary screens away from said second chute, the water and material passing through said secondary screens being received by said second chute and kept away from the tailings from said secondary screens.

19. In an apparatus of the character described, the combination of a substantially unobstructed inclined chute, means for delivering water and solid material to the upper portion of the chute and causing them to flow down the chute at a relatively high velocity, 80 a succession of primary coarse screens along the bottom of the chute and over which the material passes in succession and through each of which some of the water and a portion of the material of all grades to be retained 85 may pass while the refuse material is moved along down the chute over said screens by the water, an inclined second chute arranged lengthwise below said first chute, and a plurality of secondary screens each arranged to receive the water and solid material 90 passing through one of the primary screens and deliver the coarse material tailing off of the secondary screens away from said second chute, means for directing the water and material passing through said secondary screens to said second chute for carrying the same 95 away from the tailings from said secondary screens, and means for selectively regulating as desired the quantity of material passing 100 through the different primary screens.

20. In an apparatus of the character described, the combination of a substantially unobstructed inclined chute, means for delivering water and solid material to the upper portion of the chute and causing them to flow down the chute at a relatively high velocity, a succession of primary coarse screens along the bottom of the chute and over which the material passes in succession and through 115 which some of the water and material pass while the refuse material is moved along down the chute over said screens by the water, a plurality of inclined secondary screens each disposed to receive the water and material 120 passing through one of the primary screens and deliver the tailings from said secondary screens laterally away from said second chute, means arranged to direct the water and material passing through said secondary screens 125 130

away from the tailings therefrom, and means for selectively regulating as desired the quantity of material passing through the different primary screens.

- 5 21. In an apparatus of the character described, the combination of a substantially unobstructed inclined chute, means for delivering water and solid material to the upper portion of the chute and causing them to flow 70
10 down the chute at a relatively high velocity, a succession of screens along the bottom of the chute over which the material passes in succession and through which some of the water and material pass while the refuse material is moved along down the chute over 75
15 said screens by the water, oppositely arranged lateral secondary screens, each disposed to receive the water and material passing through one of the chute screens, and to 80
20 direct the tailings from said secondary screens to opposite sides of said chute to different desired points, means arranged to direct the water and material passing through said secondary screens away from 85
25 the tailings therefrom, and means for selectively regulating as desired the quantity of material passing through the different chute screens.

22. In an apparatus of the character described, the combination of a substantially unobstructed inclined chute, means arranged to deliver liquid and solid material under pressure to the upper portion of the chute and cause them to flow down the chute at a 90
30 relatively high velocity, a succession of spaced primary screens along the bottom of the chute and separated by imperforate chute bottom portions and over which said material passes in succession and through each 95
35 of which some of the liquid and a portion of the solid material of all grades to be retained may pass, while the refuse material is moved along down the chute by the liquid to discharge beyond the screens, secondary 100
40 screening means arranged to separately receive the liquid and solid material passing through each of the primary screens and direct the solid material tailing off of the secondary screening means to a desired point, 105
45 and means arranged to direct the liquid and fine material passing through said secondary screening means away from the solid material tailing off of the secondary screening means.

23. The combination with a boat, of a substantially unobstructed inclined chute extending lengthwise of the boat over the hold thereof, means arranged to deliver water, sand and gravel under pressure to the upper portion of the chute and cause them to flow 110
50 down the chute at a relatively high velocity, a succession of primary coarse screens along the bottom of the chute over which said material passes in succession and through each 115
55 of which some of the water and a portion of the sand and gravel of all grades to be re-

tained may pass, while the refuse material is moved along down the chute by the water to discharge beyond the screens, a plurality of secondary screens each arranged to receive the water, sand and gravel passing through 120
60 one of the primary screens and direct the gravel into the hold of the boat, said secondary screens being adapted to direct the gravel to different desired points lengthwise of the boat and means arranged to keep separated 125
65 from the gravel and to discharge overboard the water passing through the chute screens and said secondary screens.

24. The combination with a boat, of a substantially unobstructed inclined chute extending lengthwise of the boat over the hold thereof, means arranged to deliver water, sand and gravel under pressure to the upper portion of the chute and cause them to flow 130
70 down the chute at a relatively high velocity, a succession of primary screens along the bottom of the chute over which said material passes in succession and through which some of the water, sand and gravel pass, while the refuse material is moved along down the 135
75 chute by the water to discharge beyond the screens, secondary screening means arranged to receive the water, sand and gravel passing through each of the primary screens and direct the gravel into the hold of the boat, means 80
85 arranged to keep separated from the gravel and to discharge overboard the water passing through the primary screens and said secondary screening means, and means for independently controlling the discharge of 90
95 the material through the several primary screens whereby the delivery of gravel from the secondary screening means to different parts of the boat can be regulated as may be necessary to evenly load the boat. 100
105

25. The combination with a boat, of a substantially unobstructed inclined chute extending lengthwise of the boat over the hold thereof, means arranged to deliver water, sand and gravel under pressure to the upper portion of the chute and cause them to flow 110
110 down the chute at a relatively high velocity, a succession of primary screens along the bottom of the chute over which said material passes in succession and through which some of the water, sand and gravel pass, while the refuse material is moved along down the chute by the water to discharge beyond the screens, a plurality of secondary screens each arranged to receive the water, sand and gravel passing through one of the primary screens and direct the gravel into the hold of the boat, means arranged to discharge 115
120 overboard the water passing through the primary screens and said secondary screens, and independently adjustable gates for controlling the discharge through the several primary screens whereby the delivery of gravel to different parts of the boat can be regulated as desired. 125
130

26. The combination with a boat, of a substantially unobstructed inclined chute extending lengthwise of the boat over the hold thereof, means arranged to deliver water, sand and gravel under pressure to the upper portion of the chute and cause them to flow down the chute at a relatively high velocity, a succession of primary screens along the bottom of the chute over which said material 5 passes in succession and through which some of the water, sand and gravel pass, while the refuse material is moved along down the chute by the water to discharge beyond the screens, a plurality of secondary screens arranged along the chute to receive the water, sand and gravel passing through said primary screens and separate the gravel therefrom and discharge the gravel into the hold of the boat to the side of the chute, and independently adjustable gates for controlling the 10 delivery of material through the several primary screens to said secondary screens, whereby the delivery of gravel to different parts of the boat lengthwise and crosswise 15 thereof can be regulated as desired.

27. The combination with a boat, of a substantially unobstructed inclined chute extending lengthwise of the boat over the hold thereof, means for delivering solid material 10 with a relatively large proportion of water to the upper portion of the chute and causing them to flow down the chute at a relatively high velocity, a longitudinal series of spaced apart screened openings in the bottom of the chute over which the material passes in succession and through each of which some of the water and a portion of the material of all 15 grades to be retained may pass and over which the refuse material is moved along down the chute by the water, secondary screening means arranged to receive the water and material 20 passing through each of said screened openings, said secondary screening means and means cooperating therewith acting to separate the coarse material from the water and finer material and direct the separated different materials to different locations 25 on the boat.

28. In an apparatus for separating solid materials from water, the combination of a 30 stationary inclined chute the length of which is many times its width, means for delivering solid materials with a relatively large volume of water to the upper portion of the chute and causing them to flow down the chute at a relatively high velocity, said chute being constructed to provide bottom openings through 35 which the water and solid material are adapted to discharge from the chute at a plurality of points along the length of the chute, said openings being of such dimensions and character and said chute being so constructed that a portion of the water and material of all 40 grades to be retained may discharge from the chute through each of said openings while a

relatively large volume of the water will flow at a high velocity down the chute over said openings and move refuse material over the openings for discharge beyond the openings, a second chute arranged to receive the water and material discharging through said first chute openings and along which the water is adapted to flow for discharge at a desired point, and secondary screening means arranged to receive the water and material discharging from each of said chute openings and direct the coarser material away from said second chute while said second chute being disposed relatively to said secondary screening means to receive the water and fine material passing through all the openings of the first mentioned chute.

29. The combination with a boat, of a substantially unobstructed inclined chute extending lengthwise of the boat over the hold thereof, means for delivering solid material with a relatively large proportion of water to the upper portion of the chute and causing them to flow down the chute at a relatively rapid rate, there being a longitudinal series of spaced apart screened openings in the bottom of the chute over which the material passes in succession and through each of which some of the water and a portion of the material of all grades to be retained may pass and over which the refuse material is moved along down the chute by the water, secondary screening means arranged transversely of the boat axis to receive the water and material passing through each of said screened openings, and means extending beneath said screening means and arranged longitudinally of the boat for directing the water and fine material passing through said screening means to a different location on the boat.

30. In a separating apparatus, an inclined chute the length of which is many times its width, means for delivering solid materials and a relatively large volume of water to the upper end of said chute and causing them to flow down the chute at a relatively rapid rate, said chute having screened openings in the bottom at intervals along its length to each discharge a small portion of the water and materials small enough to pass through each of said screened openings, secondary screening means arranged to receive the water and material from said screened openings in the chute and divert laterally the larger particles thereof, said secondary means being adapted to pass the water and other particles received from said screened openings and a means for receiving all the water and finer particles passing through said screen means and conveying them away by the flow of the water content thereof.

HOWARD S. GERKEN.

DISCLAIMER

1,729,070.—*Howard S. Gerken*, Buffalo, N. Y. APPARATUS FOR WASHING, SEPARATING, AND GRADING MATERIALS. Patent dated September 24, 1929. Disclaimer filed June 7, 1934, by the assignee, *Gravel Products Corporation*.

Hereby enters this disclaimer to that part of the claim in said specification, which consists of claims numbered 26 and 27, which are in the following words, to wit:

“26. The combination with a boat, of a substantially unobstructed inclined chute extending lengthwise of the boat over the hold thereof, means arranged to deliver water, sand and gravel under pressure to the upper portion of the chute and cause them to flow down the chute at a relatively high velocity, a succession of primary screens along the bottom of the chute over which said material passes in succession and through which some of the water, sand and gravel pass, while the refuse material is moved along down the chute by the water to discharge beyond the screens, a plurality of secondary screens arranged along the chute to receive the water, sand and gravel passing through said primary screens and separate the gravel therefrom and discharge the gravel into the hold of the boat to the side of the chute, and independently adjustable gates for controlling the delivery of material through the several primary screens to said secondary screens, whereby the delivery of gravel to different parts of the boat lengthwise and crosswise thereof can be regulated as desired.

“27. The combination with a boat, of a substantially unobstructed inclined chute extending lengthwise of the boat over the hold thereof, means for delivering solid material with a relatively large proportion of water to the upper portion of the chute and causing them to flow down the chute at a relatively high velocity, a longitudinal series of spaced apart screened openings in the bottom of the chute over which the material passes in succession and through each of which some of the water and a portion of the material of all grades to be retained may pass and over which the refuse material is moved along down the chute by the water, secondary screening means arranged to receive the water and material passing through each of said screened openings, said secondary screening means and means cooperating therewith acting to separate the coarse material from the water and finer material and direct the separated different materials to different locations on the boat.”

DISCLAIMER

1,729,070.—*Howard S. Gerken, Buffalo, N. Y. APPARATUS FOR WASHING, SEPARATING, AND GRADING MATERIALS.* Patent dated September 24, 1929. Disclaimer filed November 14, 1935, by the assignee, *Gravel Products Corporation.*

Hereby enters disclaimer to that part of the claims in said specification which is in the following words, to wit:

“16. In an apparatus of the character described, the combination of a substantially unobstructed inclined chute, means for delivering water and solid material to the upper portion of the chute and causing them to flow down the chute at a relatively high velocity, a succession of primary screens along the bottom of the chute and over which the material passes in succession and through which some of the water and material pass while the refuse material is moved along down the chute over said screens by the water, secondary screening means arranged to separately receive the water and material passing through each of the primary screens and deliver the coarse material tailing off of the secondary screening means to a desired point, means arranged to receive the water and finer material passing through said secondary screening means and direct the same to a different point, and means for selectively regulating as desired the quantity of material passing through the different primary screens.

“17. In an apparatus of the character described, the combination of a substantially unobstructed inclined chute, means for delivering water and solid material to the upper portion of the chute and causing them to flow down the chute at a relatively high velocity, a succession of screens along the bottom of the chute over which the material passes in succession and through which some of the water and material pass while the refuse material is moved along down the chute over said screens by the water, an inclined second chute arranged lengthwise below said first chute, secondary screening means arranged to separately receive the water and material passing through each of said chute screens and direct the coarse material tailing off of the secondary screening means away from said second chute, the water and finer material passing through said secondary screening means being received and conducted by said second chute away from the tailings from said secondary screening means, and controlling means for selectively regulating the quantity of material passing through the different chute screens as desired.

“18. In an apparatus of the character described, the combination of a substantially unobstructed inclined chute, means for delivering water and solid material to the upper portion of the chute and causing them to flow down the chute at a relatively high velocity, a succession of primary coarse screens along the bottom of the chute and over which the material passes in succession and through each of which some of the water and a portion of the material of all grades to be retained may pass while the refuse material is moved along down the chute over said screens by the water, an inclined second chute arranged lengthwise below and substantially parallel to said first chute, and a plurality of secondary finer screens each arranged to receive the water and solid material passing through one of the primary screens and deliver the coarse material tailing off of the secondary screens away from said second chute, the water and material passing through said secondary screens being received by said second chute and kept away from the tailings from said secondary screens.

“19. In an apparatus of the character described, the combination of a substantially unobstructed inclined chute, means for delivering water and solid material to the upper portion of the chute and causing them to flow down the chute at a relatively high velocity, a succession of primary coarse screens along the bottom of the chute and over which the material passes in succession and through each of which some of the water and a portion of the material of all grades to be retained may pass while the refuse material is moved along down the chute over said screens by the water, an inclined second chute arranged lengthwise below said first chute, and a plurality of secondary screens each arranged to receive the water and solid material passing through one of the primary screens and deliver the coarse material tailing off of the secondary screens away from said second chute, means for directing the water and material passing through said secondary screens to said second chute for carrying the same away from the tailings from said secondary screens, and means for selectively regulating as desired the quantity of material passing through the different primary screens.

“20. In an apparatus of the character described, the combination of a substantially unobstructed inclined chute, means for delivering water and solid material to the upper portion of the chute and causing them to flow down the chute at a relatively high velocity, a succession of primary coarse screens along the bottom of the

chute and over which the material passes in succession and through which some of the water and material pass while the refuse material is moved along down the chute over said screens by the water, a plurality of inclined secondary screens each disposed to receive the water and material passing through one of the primary screens and deliver the tailings from said secondary screens laterally away from said second chute, means arranged to direct the water and material passing through said secondary screens away from the tailings therefrom, and means for selectively regulating as desired the quantity of material passing through the different primary screens.

"21. In an apparatus of the character described, the combination of a substantially unobstructed inclined chute, means for delivering water and solid material to the upper portion of the chute and causing them to flow down the chute at a relatively high velocity, a succession of screens along the bottom of the chute over which the material passes in succession and through which some of the water and material pass while the refuse material is moved along down the chute over said screens by the water, oppositely arranged lateral secondary screens, each disposed to receive the water and material passing through one of the chute screens, and to direct the tailings from said secondary screens to opposite sides of said chute to different desired points, means arranged to direct the water and material passing through said secondary screens away from the tailings therefrom, and means for selectively regulating as desired the quantity of material passing through the different chute screens.

"22. In an apparatus of the character described, the combination of a substantially unobstructed inclined chute, means arranged to deliver liquid and solid material under pressure to the upper portion of the chute and cause them to flow down the chute at a relatively high velocity, a succession of spaced primary screens along the bottom of the chute and separated by imperforate chute bottom portions and over which said material passes in succession and through each of which some of the liquid and a portion of the solid material of all grades to be retained may pass, while the refuse material is moved along down the chute by the liquid to discharge beyond the screens, secondary screening means arranged to separately receive the liquid and solid material passing through each of the primary screens and direct the solid material tailing off of the secondary screening means to a desired point, and means arranged to direct the liquid and fine material passing through said secondary screening means away from the solid material tailing off of the secondary screening means.

"23. The combination with a boat, of a substantially unobstructed inclined chute extending lengthwise of the boat over the hold thereof, means arranged to deliver water, sand and gravel under pressure to the upper portion of the chute and cause them to flow down the chute at a relatively high velocity, a succession of primary coarse screens along the bottom of the chute over which said material passes in succession and through each of which some of the water and a portion of the sand and gravel of all grades to be retained may pass, while the refuse material is moved along down the chute by the water to discharge beyond the screens, a plurality of secondary screens each arranged to receive the water, sand and gravel passing through one of the primary screens and direct the gravel into the hold of the boat, said secondary screens being adapted to direct the gravel to different desired points lengthwise of the boat and means arranged to keep separated from the gravel and to discharge overboard the water passing through the chute screens and said secondary screens.

"24. The combination with a boat, of a substantially unobstructed inclined chute extending lengthwise of the boat over the hold thereof, means arranged to deliver water, sand and gravel under pressure to the upper portion of the chute and cause them to flow down the chute at a relatively high velocity, a succession of primary screens along the bottom of the chute over which said material passes in succession and through which some of the water, sand and gravel pass, while the refuse material is moved along down the chute by the water to discharge beyond the screens, secondary screening means arranged to receive the water, sand and gravel passing through each of the primary screens and direct the gravel into the hold of the boat, means arranged to keep separated from the gravel and to discharge overboard the water passing through the primary screens and said secondary screening means, and means for independently controlling the discharge of the material through the several primary screens whereby the delivery of gravel from the secondary screening means to different parts of the boat can be regulated as may be necessary to evenly load the boat.

"25. The combination with a boat, of a substantially unobstructed inclined chute extending lengthwise of the boat over the hold thereof, means arranged to deliver water, sand and gravel under pressure to the upper portion of the chute and

cause them to flow down the chute at a relatively high velocity, a succession of primary screens along the bottom of the chute over which said material passes in succession and through which some of the water, sand and gravel pass, while the refuse material is moved along down the chute by the water to discharge beyond the screens, a plurality of secondary screens each arranged to receive the water, sand and gravel passing through one of the primary screens and direct the gravel into the hold of the boat, means arranged to discharge overboard the water passing through the primary screens and said secondary screens, and independently adjustable gates for controlling the discharge through the several primary screens whereby the delivery of gravel to different parts of the boat can be regulated as desired."

"28. In an apparatus for separating solid materials from water, the combination of a stationary inclined chute the length of which is many times its width, means for delivering solid materials with a relatively large volume of water to the upper portion of the chute and causing them to flow down the chute at a relatively high velocity, said chute being constructed to provide bottom openings through which the water and solid material are adapted to discharge from the chute at a plurality of points along the length of the chute, said openings being of such dimensions and character and said chute being so constructed that a portion of the water and material of all grades to be retained may discharge from the chute through each of said openings while a relatively large volume of the water will flow at a high velocity down the chute over said openings and move refuse material over the openings for discharge beyond the openings, a second chute arranged to receive the water and material discharging through said first chute openings and along which the water is adapted to flow for discharge at a desired point, and secondary screening means arranged to receive the water and material discharging from each of said chute openings and direct the coarser material away from said second chute while said second chute being disposed relatively to said secondary screening means to receive the water and fine material passing through all the openings of the first mentioned chute.

"29. The combination with a boat, of a substantially unobstructed inclined chute extending lengthwise of the boat over the hold thereof, means for delivering solid material with a relatively large proportion of water to the upper portion of the chute and causing them to flow down the chute at a relatively rapid rate, there being a longitudinal series of spaced apart screened openings in the bottom of the chute over which the material passes in succession and through each of which some of the water and a portion of the material of all grades to be retained may pass and over which the refuse material is moved along down the chute by the water, secondary screening means arranged transversely of the boat axis to receive the water and material passing through each of said screened openings, and means extending beneath said screening means and arranged longitudinally of the boat for directing the water and fine material passing through said screening means to a different location on the boat.

"30. In a separating apparatus, an inclined chute the length of which is many times its width, means for delivering solid materials and a relatively large volume of water to the upper end of said chute and causing them to flow down the chute at a relatively rapid rate, said chute having screened openings in the bottom at intervals along its length to each discharge a small portion of the water and materials small enough to pass through each of said screened openings, secondary screening means arranged to receive the water and material from said screened openings in the chute and divert laterally the larger particles thereof, said secondary means being adapted to pass the water and other particles received from said screened openings and a means for receiving all the water and finer particles passing through said screen means and conveying them away by the flow of the water content thereof."
